(57) **CLAIM**

The ornamental design for a tread portion of an automobile tire, as shown and described.

DESCRIPTION

FIG. 1 is a perspective view of a tread portion of an automobile tire according to our design;

FIG. 2 is a front view thereof;

FIG. 3 is a top view thereof;

FIG. 4 is a right side view thereof;

FIG. 5 is a left side view thereof;

FIG. 6 is a rear view thereof;

FIG. 7 is a fragmentary enlarged font view showing the details of the tread portion thereof; and,

FIG. 8 is a section view taken along line 8-8 in FIG. 7.

Broken lines in the drawing figures are used to show portions of the tire that are not claimed, and thus form no part of the claimed invention.
